UNITED STATES PATENT OFFICE.

STEPHEN SCHWARTZ, OF CLEVELAND, OHIO, ASSIGNOR, BY MESNE ASSIGNMENTS, TO
LOUIS F. SCHROEDER, OF CLEVELAND, OHIO.

FOUNTAIN-FAUCET.

1,114,051.

Specification of Letters Patent. Patented Oct. 20, 1914.

Application filed January 23, 1911, Serial No. 604,040. Renewed March 13, 1914. Serial No. 824,553.

To all whom it may concern:

Be it known that I, STEPHEN SCHWARTZ, a citizen of the United States, residing at Cleveland, in the county of Cuyahoga and State of Ohio, have invented certain new and useful Improvements in Fountain-Faucets, of which the following is a specification.

My invention relates to improvements in fountain or drinking faucets, the primary object of the invention being to provide a generally improved sanitary drinking faucet of simple, cheap, and efficient construction, and particularly designed and adapted 10 for use in lieu of the ordinary faucet whereby the necessity for the provision of a drinking cup may be dispensed with.

A further object of the invention is to provide a combined fountain and filtering 20 faucet adapted to be attached to an ordinary faucet valve body in lieu of the spout or nozzle portion thereof, the fountain cup or spout being rotatably mounted whereby the same is adapted in its normal or depending 25 position for use as an ordinary nozzle or discharge spout, and when it is desired to use the same as a drinking fountain the rotatably mounted fountain cup or faucet may be turned to a reverse or upstanding vertical position, thus directing the discharging 30 stream upwardly in fountain form.

With the above mentioned and other ends in view, the invention consists in the novel construction, arrangement, and combination of parts, hereinafter described, 35 illustrated in one of its embodiments in the accompanying drawings, and particularly pointed out in the appended claims.

Referring to the drawings, forming a part 40 of this specification, Figure 1, is a side elevation of the improved fountain or drinking faucet as it appears used as an attachment to an ordinary faucet valve body. Fig. 2, a front or end view of the same, a portion 45 of the walls of the fountain cup or spout being broken away for the purpose of clearer illustration of the parts. Fig. 3, a central vertical sectional view of the valve head attachment and rotatably mounted 50 fountain cup or spout detached from the faucet valve body. Fig. 4, a perspective view of the valve stem and head. Fig. 5, a cross sectional view through the improved fountain cup or spout taken on line 5—5 of 55 Fig. 1. Fig. 6, a detail view of the retaining

washer used in connection with the valve stem and head.

Similar numerals of reference designate like parts throughout all the figures of the drawings.

In the present embodiment of my invention I have shown the same designed and adapted for use as an attachment in connection with an ordinary faucet valve body 1, to be used in lieu of the ordinary discharge spout or nozzle. The improved fountain or drinking faucet comprises a valve stem or pipe 2, terminating in a valve head 2^a, said valve head being provided with oppositely disposed outlet ports 2^c, intersecting 60 the main discharge opening or duct 2^d.

As a convenient means for attaching the valve stem or pipe 2, to the main supply pipe or discharge branch 1^a, of the valve body, said valve pipe or stem may be threaded within the discharge branch 1^a, as shown.

A fountain cup or spout 3, is rotatably mounted upon the valve head 2^a, by means of a sleeve head 3^a, and as a means for forming a proper connection or fit between the 65 valve head 2^a and sleeve head 3^a, said valve head is preferably tapered or beveled as shown to fit within the correspondingly beveled or flared bearing opening of the sleeve head 3^a.

As a means for adjusting and retaining the sleeve head 3^a, upon the tapered valve head 2^a, said valve head is provided at its end with a threaded stud 2^e, adapted to carry a washer 4, fitted thereon. The washer 4, 70 is retained and adjustably mounted upon the stud 2^e, by means of an adjusting screw 5, threaded in the threaded stud, and as a means for preventing the rotation of the washer 4, upon the stud 2^e, the latter is provided with a flattened portion 4^a, adapted 75 to engage and coact with a correspondingly formed portion 4^b, in the opening of the washer 4.

The sleeve head 3^a, and stem or neck portion 3^b, of the fountain spout is provided with an outlet port or duct 6, adapted to be brought into registry with the outlet ports or ducts 2^c, when the fountain cup is moved either to its depending position or its reverse upwardly extending position, said outlet port or duct communicating with the chamber of the cup or spout through a perforated or strainer cup 7, the side walls of said strainer cup being provided with per-

forations 7^a, and lined with suitable foraminous or strainer material 8, such as fine wire gauze or perforated sheet metal, or the like, and as a means for removably maintaining 5 said foraminous or strainer metal within the cavity of the cup, the latter is provided with a threaded thumb cap 9, carrying a washer 10, and disk plate 11, said disk plate being disposed immediately beneath the strainer 10 material 8.

As a means for removably mounting the second or strainer cup 7, within the fountain cup or spout 3, said cup 7, is provided with a threaded stud portion 7^b, threaded in a 15 similarly shaped threaded opening, said stud portion being provided with a duct adapted to register and communicate with the outlet port or duct 6, and having an angular portion 7^c, for the reception of a key 20 or wrench member, whereby said strainer cup may be revolved in the act of securing or removing the same within the fountain cup or spout 3.

A fountain cap 12, is removably secured 25 to the lower or discharge portion of the fountain cup or spout preferably by means of screw threads, said fountain cap being provided with a central opening or orifice 12^a, for the discharge of the fountain stream 30 in a well known and understood manner.

From the foregoing description, taken in connection with the accompanying drawings, the operation and advantages of my invention will be readily understood.

Having thus described my invention, what 35 I claim and desire to secure by Letters Patent is,

1. In a fountain faucet, a rotatably mounted fountain cup provided with an inlet port 40 at one end and a central discharge opening at the other and having an enlarged cylindrical shaped chamber, a second cup having an enlarged strainer chamber communicating 45 with said inlet port and provided with perforated cylindrical walls spaced from the walls of said fountain cup to provide an annular chamber between the walls of said cups, and an imperforate cap threaded to the

outer end of said second cup whereby access may be obtained to said enlarged strainer 50 chamber and spaced inwardly from said central discharge opening.

2. In a fountain faucet, a rotatably mounted fountain cup provided with inlet and outlet ports, a cylindrical shaped perforated cup 55 mounted in and spaced from the walls of said fountain cup to form an annular chamber within the walls of the latter, said perforated cup being provided with an enlarged chamber communicating with said inlet port, 60 a strainer member mounted within said enlarged chamber of said strainer cup, and an imperforate thumb cap threaded to the outer end of said strainer cup and adapted to removably retain said strainer member therein. 65

3. In a fountain faucet, the combination with a rotatably mounted fountain cup provided with an inlet port opening at one end and a central discharge opening at the other; of a cylindrical strainer cup having an enlarged strainer chamber communicating with said inlet port and having its cylindrical walls perforated and spaced from the walls of said fountain cup to provide an annular chamber between the walls of said cups, a 75 cylindrical strainer member mounted in said strainer chamber, and a cap removably secured to the outer end of said perforated cup and adapted to removably retain said cylindrical strainer member therein. 80

4. In a fountain faucet, a fountain cup provided with a sleeve head and having a duct communicating with the latter and provided at one end with a threaded opening, a 85 perforated cup provided with a threaded hollow stud portion mounted in said threaded opening, said threaded stud being provided with an angular key receiving portion, and an imperforate cap threaded to the lower end of said perforated cup. 90

In testimony whereof I have affixed my signature in presence of two witnesses.

STEPHEN SCHWARTZ.
